UNITED STATES PATENT OFFICE.

MILO COVEL, OF CHICAGO, ILLINOIS.

MACHINE FOR STRAIGHTENING AND HAMMERING SAWS.

SPECIFICATION forming part of Letters Patent No. 380,865, dated April 10, 1888.

Application filed December 27, 1887. Serial No. 259,001. (No model.)

To all whom it may concern:

Be it known that I, MILO COVEL, of Chicago, county of Cook, and State of Illinois, have invented certain new and useful Improvements 5 in Machines for Straightening and Hammering Saws, of which the following is a full, clear, and exact description, that will enable others to make and use the same, reference being had to the accompanying drawings, forming a part of 10 this specification.

This invention relates to improvements in that class of machines that are more especially intended for dressing band-saws; and the same 15 consists of certain novel features in the construction, combination, and arrangement of the several parts, as will be hereinafter set forth.

Figure 1 is a side elevation of a machine embodying my improved features; Fig. 2, a 20 horizontal section in the plane 2, Fig. 1; Fig. 3, a horizontal section in the plane 3, Fig. 1; and Fig. 4, a vertical section in the plane 4, Fig. 3.

Referring to the drawings, A represents the 25 supporting frame-work, which may be of any suitable form or dimensions.

B B' are two companion shafts arranged vertically, and have the two swaging-rolls B² B³ mounted thereon. The upper ends of these 30 shafts have suitable journal-bearings in the slide-blocks B⁴ B⁵, which are provided with the downwardly-projecting parts a a', connected with the cross-head B⁶, as shown in Figs. 1 and 4. This cross-head is constructed 35 in two parts, which parts are connected by the bolted straps a² a². The vertical shafts B B' pass down through the cross-head B⁶ and have bearings therein. The shaft B projects just far enough below the cross-head to have the 40 pinion a³ rigidly mounted thereon, while the companion shaft B' extends down to a point near the floor, as shown in Figs. 1 and 4. The shaft B' is also provided with the lower journal-bearing, a⁴, the supporting ends of which 45 are bolted to the lower ends of the standards C C, the upper ends of which extend above the top of the frame-work and are secured to the same by means of the bolts a⁵. The standards C C form guides for the vertical movement of 50 the slide-blocks B⁴ B⁵ and the cross-head B⁶ in

the vertical adjustment of the shafts B B'. The spur-wheel C is feathered on the shaft B' just underneath the lower bearing, so as to permit of a vertical movement of said shaft. The pinion a⁶ is rigidly mounted on the shaft 55 B' between the lower bearing, a⁴, and the cross-head B⁶, and engages with the pinion a³ on the vertical shaft B, for the purpose of transmitting the required motion. The spur-wheel C engages with the pinion b, rigidly mounted on 60 the lower part of the vertical shaft C², (see Figs. 1, 2, and 4,) which is in turn provided with suitable journal-bearings in the frame-work. The bevel gear-wheel C³ is mounted on the lower end of the shaft C², and engages 65 with the corresponding pinion, b', mounted on the inner end of the horizontal shaft C⁴, journaled in the lower part of the frame-work, as shown in Fig. 2.

C⁵ is a gear-wheel mounted on the shaft C⁴, 70 which engages with the pinion b², mounted on the companion horizontal driving-shaft C⁶, having the band-pulleys C⁷ C⁸, which receive the driving-belt from the motive power. By this system of shafts and gear-wheels the required 75 motion is transmitted to the vertical shafts B B' and the stretching and straightening rolls B² B³, mounted on the upper end of the same.

The connecting-band b³ is ordinarily composed of a strip of leather or other flexible 80 material, and has one end attached to the cross-head B⁶, the other end being secured to the shaft b⁴, so that when said shaft is rotated the band will be wound up or unwound in accordance with the direction in which the shaft 85 is rotated. This shaft is operated by means of the hand-crank b⁶, and is for the purpose of raising and lowering the shafts B B', so as to bring the swaging-rolls into position to have frictional contact with any particular spot on 90 the surface of the saw-plate.

It is well known that there are some parts of a band-saw that require a little more straining and stretching than other parts, and there are also spots that require a different treatment than they would receive by simply running the saw through with the same pressure on all parts alike. The faces of the rolls are less than the width of the saw, so that one edge 95 may be strained without having contact with 100

the other edge. The ratchet-wheel d and the pawl d' lock the shaft b^4 at any point to which the vertical shafts B B' may be adjusted. The clamp D (see Fig. 4) connects the upper ends 5 of the standards or guides C C , and is attached at one end by means of the pivot-bolt d^2 and adjustably secured at the opposite end by the clamping-bolt d^3 , by which means the standards are stiffened against spreading or yielding and adjusted with reference to each other, so that the wear of the frictional contacting surfaces may be compensated for and the proper adjustment maintained. By slackening back on the bolt d^3 this end of the clamp or 15 yoke D may be raised to permit of the insertion or removal of the endless saw. The normal position of the rolls B^2 B^3 , as shown, is just far enough apart to permit of the easy insertion of the saw, which passes between the 20 rolls in a vertical plane instead of lying flat. The roll B^2 and the upper end of the shaft upon which it is mounted have also a slight lateral adjustment or movement, so as to clamp the saw between the two rolls. The inward pressure 25 and movement are accomplished by means of the cam-shaft d^4 and the hand-lever d^5 , mounted thereon, as shown in Fig. 4. This cam-shaft is journaled in the slide-block B^4 , and has a bearing against the standard C on 30 that side. The lower end of the downwardly-extending part a of the slide-block B^4 has a slight pivotal movement on the bolt d^6 , in order to conform to the lateral movement of the roll B^2 . The ends of the spring d^7 are attached to 35 the slide-blocks B^4 B^5 , respectively, said spring serving to return the roll B^2 to a normal position when released from the pressure of the cam-shaft.

By means of the cam-shaft and operating-lever the operation of the machine is easily 40 controlled and the pressure on the saw-blade varied—that is, from very light to very heavy, as the different parts of the saw may require.

On the table-bed D' or top of the machine 45 (see Fig. 3) are placed the anvil-blocks D^2 D^3 , arranged diagonally and on opposite sides of the rolls B^2 B^3 , so as to bring the faces of the anvils in line with the pathway of the saw and on the respective sides of the same, where- 50 by either side of the saw may be hammered before and after passing through the rolls.

Practical experience has proven that in order to keep a saw in a first-class condition it must be hammered in addition to being passed 55 between rollers. By this arrangement both the hammering and rolling process are jointly done in the same machine and in conjunction, thereby doing the work in a much more efficient manner and with greater facility than if 60 performed separately, as either the rolls or anvils may be used, or both, without having to transfer the saw back and forth from one machine to another, a heavy saw requiring a number of persons to handle it.

65 The saw S , as shown in Figs. 3 and 4, is supported vertically edgewise when being dressed, instead of lying flat and passing be-

tween swaging-rolls occupying a horizontal position, as is usually the case. Holding the saw edgewise is the most natural position, as the same is less liable to be warped or sprung during the process of dressing, and the operator is enabled to carefully examine the surface of the saw-plate by looking down over the same while standing in an erect position.

70 The rectangular bracket-plates E E' are adjustably secured to opposite ends of the machine (see Fig. 1) at a point below and in line with the path of the saw. The faces of these plates will present a bright reflecting-surface 80 to bring out plainly to the eye of the operator all defects in the saw-plate as he looks downward over the same. These plates may be set at any desired angle with reference to the line of vision.

75 The shelf F (see Fig. 4) provides a convenient place for keeping the tools required for use in connection with the machine.

Having thus described my invention, what I claim, and desire to secure by Letters Patent, 90 is—

1. In a machine of the character herein set forth, the combination, with the supporting-frame, of the vertical shafts B B' , the sliding bearing-blocks in which said shafts are journaled, the companion swaging-rolls rigidly mounted on the upper ends of said shafts, and means for imparting a vertical movement to said shafts, whereby the swaging-rolls may be brought to bear on any desired part of the saw-plate, substantially as and for the purpose set forth.

95 2. In a machine of the character herein set forth, the combination, with the vertically-ar- 105 ranged shafts having stretching and straight- ening rolls on the upper ends thereof, of the slide-blocks B^4 B^5 , provided with the down- wardly-projecting parts a a' , the cross-head B^6 , constructed in two parts and connected by the straps a^2 a' , the standards and guides C C , the flexible band b^3 , the winding-shaft b^4 , and the hand-crank for rotating said winding-shaft, substantially as and for the purpose set forth.

110 3. The combination, with the supporting-frame, of the vertical shafts B B' , the means 115 described for transmitting motion from one to the other, the spur-wheel C' , mounted on the vertical shaft B' , the pinion b , the vertical shaft C^2 , on which said pinion is mounted, the bevel gear-wheel C^3 , also mounted on the shaft C^2 , the bevel-pinion b' , the horizontal shaft C^4 , the gear-wheel C^5 , the pinion b^2 , and the companion horizontal shaft C^6 , whereby the required motion is transmitted to the vertical shafts carrying the swaging-rolls, substantially 125 as set forth.

120 4. The combination, with the standards or guides C C , of the clamp or yoke D , pivoted at one end to one of said standards and adjustably secured at the other end to the companion standard, substantially as and for the purpose set forth.

125 5. In a machine of the character herein set forth, the combination, with the vertical shaft

B, having a swaging-roll mounted on the upper end thereof and adapted to have a slight lateral adjustment, of the shaft B', carrying the companion swaging-roll, the standard or 5 guide C on that side, the cam-shaft d⁴, and the hand-lever d⁵, whereby said roll is forced in the direction of the other by hand, and the spring d⁶, for automatically separating said rolls when released from the pressure of the 10 cam-shaft, substantially as and for the purpose set forth.

6. In a machine of the character herein set forth, the combination, with the table-bed, of the anvil-blocks D² D³ and the swaging-rolls, 15 said anvils being placed on opposite sides of said rolls and arranged diagonally relative to each other for the purpose of bringing the faces

of said anvils in line with the pathway of the saw and on opposite sides of the same, whereby the saw may be operated upon from either side 20 before or after the same has passed through the swaging-rolls, substantially as and for the purpose set forth.

7. Jointly with the saw stretching and straightening machine, the reflecting-plates E 25 E', adjustably secured to the frame-work of said machine and located at opposite ends of the same and in line with the path of the saw, substantially as and for the purpose set forth.

MILO COVEL.
